CLAIM

The ornamental design for a cord for electronics, as shown and described herein.

DESCRIPTION

FIG. 1 is a top perspective view of the preferred embodiment of the cord for electronics of the instant invention, showing the new design;

FIG. 2 is a bottom perspective view of the preferred embodiment of the cord for electronics of the instant invention of FIG. 1;

FIG. 3 is a top plan view of the preferred embodiment of the cord for electronics of the instant invention of FIG. 1;

FIG. 4 is a bottom plan view of the preferred embodiment of the cord for electronics of the instant invention of FIG. 1;

FIG. 5 is an elevational view of the left side of the preferred embodiment of the cord for electronics of the instant invention of FIG. 1;

FIG. 6 is an elevational view of the right side of the preferred embodiment of the cord for electronics of the instant invention of FIG. 1;

FIG. 7 is an elevational view of the front side of the preferred embodiment of the cord for electronics of the instant invention of FIG. 1; and,

FIG. 8 is an elevational view of the back side of the preferred embodiment of the cord for electronics of the instant invention of FIG. 1.
